UNITED STATES PATENT OFFICE

WILLIAM R. CARTWRIGHT, OF EAST NORWALK, CONNECTICUT

LOOM ATTACHMENT

Application filed October 23, 1929. Serial No. 401,785.

This invention relates generally to loom attachments and the improvements are directed to novel and unique means whereby lettering formed in a fabric during the weaving process may be disposed in a horizontal plane and at right angles to the edges of said fabric.

Primarily, the object of the present invention resides in the provision of an eccentric roller or rollers adapted to be associated with a loom in a manner to cause filling threads forming letters or other designs to be exactly at right angles to the edges of the fabric, and thus preventing a curvature weave so common in present-day products.

Another object is to provide means in the form of an eccentric roller adapted to compensate for congestion of the outer threads by stretching slightly the center threads to the end that the above recited object may be accomplished.

Those skilled in the art to which this invention appertains are aware that in the ordinary process of weaving, especially in narrow fabric looms, the warp threads pass through a wire reed which keeps the same straight and which regulates the width of the fabric being woven; these wire reeds, called front reeds, being fastened on the batten between the shuttles. After each movement of the shuttles by which a filling thread is passed between the warp threads, the batten moves forward and presses the front reeds against the filling threads, and on each of these forward movements of the batten the front reed pushes the warp threads out a little wider than the width of the fabric being woven. In view of the foregoing there is a tendency to create a slackness or congestion of the outer threads as the batten goes back thus causing a slight curve on the fabric when it passes over straight breast-beam rollers, this curve being particularly noticeable when block type letters are being woven.

In order to straighten out this curvature it is proposed to mount one or more rollers on a rod attached to the breast-beam of a loom, said roller or rollers being then squared in line with the front reeds for final adjustment, collectively, or individually, to meet the varying conditions of the weaving.

As will presently appear, these varying conditions, due to difference in size of yarn, tension, strength of reeds and many other factors, are compensated for by providing rollers having a diminishing curve, thus permitting of adjustment to meet any condition of weaving from neutral to the highest point of curvature.

With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

Figure 1 is a partial plan view of a loom adapted to produce narrow fabric, illustrating a portion of the usual breast-beam and the application of the present invention thereto.

Fig. 2 is a transverse sectional view, taken on the line 2—2 of Fig. 1, the showing being somewhat diagrammatical.

Fig. 3 is an elevational, slightly enlarged, of one of the improved rollers.

Fig. 4 is another view of the roller and showing Fig. 3 in plan.

Fig. 5 is a transverse section taken on the line 5—5 of Fig. 3.

Fig. 6 is a similar sectional view taken on the line 6—6 of Fig. 3.

Fig. 7 illustrates a portion of a narrow fabric presenting lettering produced by the application of my invention.

Referring now more in detail to the accompanying drawings, wherein like characters of reference denote similar parts throughout the several views, let 10 indicate the breast-beam of a narrow fabric loom, the latter also including the shuttles 11 on a batten. As shown in Fig. 2, the numeral 12 indicates the warp threads before the intersection of filling threads carried by said shuttles, while 13 denotes the woven fabric, in which letters may be formed by the intersection of the filling or weft threads.

As previously pointed out it is proposed to introduce my eccentric rollers at the rear of the breast-beam to permit the passage of

the fabric thereover, and to this end two-part clamping members 14 are coupled to said breast-beam 10, as shown in Fig. 2, said members 14 being formed to provide a journal bearing for the rod 15 positioned coextensive with said breast-beam 10, said rod supporting the eccentric rollers 16.

Referring now to Figs. 3 to 6 of said drawings, it will be observed that each of the rollers is provided with a central bore 16a for the reception of said rod 15, threaded apertures 17 and 18 being extended into said bore to receive set-screws 19, (see Fig. 2), whereby the rollers may be mounted on said rod 15 in the desired position. Each of the rollers is provided with oppositely disposed headed portions 20 and 21, which are formed during the turning of the medial curvature portion 22 in a lathe or the like.

Said medial portion 22 presents what may be termed a diminishing curve, 23 indicating the high point and 23a the low point, as shown in Fig. 3, while 24 and 25 denote the intermediate curves, (see Fig. 4) arranged substantially at right angles to said high and low points and disposed on opposite sides of said roller. As clearly shown in said Figs. 3 and 4, the curvature extends longitudinally of the roller in a manner that the radius of the curvature increases from the high point 23 to the intermediate points 24 and 25 and as said radius approaches the low point it becomes substantially equal to the radius of the roller or the headed portions 20 and 21.

After the rollers are positioned on said rod 15 and the clamps affixed to the breast-beam, said rollers are first squared in line with the front reeds for final adjustment to meet the varying conditions of weaving, as set forth hereinbefore, and in view of the curvature, above described, the effect of the congestion in the outer threads is overcome by slightly stretching the center threads by a graduated tension which is greatest at the center. In other words, a greater tension is exerted on the center threads by the curvature of the rollers which slightly stretches those threads so that when the woven fabric passes through the take-up rollers and this tension is relieved, the threads spring back due to their own elasticity and thus the natural tendency to produce a curvature during the weaving, is reduced to a minimum.

In view of the provision of the diminishing curve said rollers may be adjusted on said rod 15, by manipulating said set-screws 19, to meet any condition of weaving from neutral to the highest point of curvature.

Various slight changes might be made in the general form and arrangement of the parts described without departing from the invention, and hence I do not limit myself to the precise details set forth, but consider myself at liberty to make such changes and al-

terations as fairly fall within the spirit and scope of the appended claims.

I claim:

1. In a loom, the combination with a breast-beam, of a roller positioned adjacent thereto, said roller having a diminishing curved portion to stretch the center threads of a fabric passing thereover and being susceptible of adjustment by rotation to present different contours to the fabric passing thereover. 75

2. A roller adapted to be adjustably attached to a loom for the passage of a woven fabric thereover, said roller having a medial curved portion presenting oppositely disposed high and low points and oppositely disposed intermediate points. 80

3. A roller adapted to be attached to a loom adjacent the breast-beam thereof and in the path of a moving woven fabric, said roller presenting a diminishing curved position including high and low points whereby said roller may be susceptible of adjustment to meet varying weaving conditions and to exert a tension on the center threads of the fabric. 85

4. In a loom, the combination with a breast-beam, of a roller positioned adjacent thereto, said roller presenting a curved surface adapted to straighten a fabric passing thereover by placing a graduated tension on the inside threads, such tension being greatest in the center and which on release will permit said center threads to spring back in line with the outer threads, said roller being susceptible of adjustment by rotation to present different contours to the fabric passing thereover. 90

In testimony whereof I affix my signature.

WILLIAM R. CARTWRIGHT.
